Des. 1058

Ezra Clark, of Portland, Me.

Assignor to

Jeth Clark, of West Brook, Me.

Letters Patent No. 1058 Dated Oct. 26. 1858.

The schedule referred to in these Letters Patent and making part of the same —

To all whom it may concern:

Be it known that I, Ezra Clark, of Portland, in the County of Cumberland and State of Maine, have invented and produced a new and original design for a cast metallic tablet, to be used in protecting wall from heat and smoke for Gas Cooking apparatus and also for any other purpose for which such tablet may be proper.

The Tablet as cast is about seventeen inches long, and ten inches wide.

Fig. 1. in the accompanying drawings, and forming part of my specification is a perspective elevation of my design with a gas burner for cooking annexed.

Fig. 2. is a section of the same taken through the line A. B.

Fig. 3. is a section of the same, taken through the line C. D.

I do not mean to limit myself to this exact size or proportion, the ornamental portions remaining as described, and shown in the accompanying drawings, nor do I claim the gas burner for cooking as therein shown.

But what I claim as new and of my own invention, is the ornamental design for a cast tablet of iron or other metal as set forth and represented in the accompanying Photographic views.

Witnessed.

Frederick Fox.

Edward Fox, Jr.

Ezra Clark.
